PAPER HOLDER

Peer A. Locke, Rome, N.Y.

Application April 26, 1957, Serial No. 655,287

2 Claims. (Cl. 242—55.54)

This invention relates to holders for rolls of paper, foil, and similar materials and more particularly to roll holders of the type wherein individual sheets or lengths thereof are to be torn therefrom.

Heretofore various means have been provided for holding paper rolls for ready dispensing of the sheets thereon particularly of the so-called horizontal roller type in which the roll of paper is inserted upon a spindle mounted in end journals for rotation therein. These generally have been of rather unsatisfactory construction for many applications and are often easily unrolled, spilling large numbers of sheets of paper on the floor in an unsightly and messy manner and also they have been very difficult to operate, particularly with one hand so that only the desired sheets of paper are torn therefrom. To overcome the disadvantage of this type of horizontal paper holder various types of angularly disposed dispensers have been suggested including those in which the paper roll is disposed about a spindle mounted at an angle to the vertical with some base member which acts as a frictional drag upon the rotation of the paper on the roll. These latter devices have been satisfactory for certain applications but generally have been unsatisfactory in their control of the friction resisting the rotation of the roll.

Accordingly it is an object of the present invention to provide an improved roll holder of the angularly disposed type. It is another object of the present invention to provide a paper roll holder of simplified and attractive construction that is economical to manufacture. It is another object of the present invention to provide a paper roll holder of the angularly inclined type wherein the frictional control of the rotation thereof is precisely regulated. It is another object of the present invention to provide a paper roll holder of the angularly disposed type that is more flexible in operation and may be mounted at a wide variety of angles to the vertical. It is a still further object of the present invention to provide a paper roll holder that may be easily and economically molded of a simple plastic material that will be pleasing and attractive in appearance and yet functional and accurately controllable in operation. These and other and further objects will be in part apparent and in part pointed out as the specification proceeds.

In the drawings:

Figure 1 is a partial perspective view of a paper roll holder according to the present invention;

Figure 2 is a partial longitudinal sectional view of the holder of the present invention;

Figure 3 is a view similar to Figure 2 of another embodiment of the present invention.

Referring now to Figure 1 the paper roll holder 10 comprises generally a bracket 12, having at one end a wall plate 14 and at the other end 16 a paper supporting spindle 18 about which the paper roll may be disposed. As may be readily seen the bracket 12 is of a relatively thin yet wide sheet-like construction tapering somewhat

2

from the wall plate 14 to the spindle holding end 16. The wall plate 14 is joined to the main portion of the bracket 12 by reinforcing web 20 which serves to strengthen the angular displacement of the two end portions of the bracket 12 to securely hold the paper roll in the desired angular position.

The spindle 18, as shown in Figure 2, is advantageously of a hollow nature and has a bottom flange 22 and a stub shaft 24 extending downwardly therefrom. Spindle 18 is mounted in a hole 26 in end 16 of bracket 12. After the spindle 16 is inserted through the hole 26 a washer 28 is applied over the end thereof and the end of the shaft 24 is formed over so as to securely but rotatably hold the spindle in the bracket 12. Alternatively other fastening means such as snap or threaded means may be used in place of pressure forming.

Spindle 18 is of a generally hollow cylindrical nature and normally extends slightly over half way through the roll of paper to be mounted thereon. It should be understood, however, that a solid spindle may be used. This provides a firm mounting for the roll of paper and also permits utilization of the central core for the placement of a deodorant or other object such as a reserve or auxiliary supply of paper or the like.

In the construction shown the spindle 18 is free to rotate within the bracket 12 in hole 26 subject only to the restriction of the friction between the flange 22, washer 28 and the bracket 12. Rotation of spindle 18 is thus accurately controlled by the dimension of the flange 22 and the washer 28. The frictional forces resisting the rotation of the spindle therefore do not significantly depend upon the size of the paper roll placed thereon nor on the diameter thereof. This results in a more uniform rotation and permits greater variation in angle from the vertical to adapt the paper holder to the particular situation encountered.

In operation the spindle 18 is made with a diameter approximately the same size as the diameter of the core of the paper roll to be inserted thereon. A snug fit is thus assured such that the paper roll will rotate with the spindle 18 within the hole 26 of the bracket 12. Thus when it is desired to remove a section of paper from the roll the loose end may be conveniently pulled more or less at right angles to the axis of the roll of paper and when it is desired to tear it off a downward or angular pull at an angle to the axis of the roll of paper will separate the sheet from the roll itself. During the substantially right angle pull the roll will rotate with the spindle 18 but when a pull is exerted at an angle to the axis of the paper the friction between flange 22 and bracket 12 is increased sufficiently so that the paper is torn off rather than producing further rotation of the roll.

In the normal rest position the friction of the washer and flange about the bracket 12 is sufficient to prevent rotation of the roll of paper by itself so that the paper cannot become easily unwound therefrom so that it falls on the floor in a mess as with prior horizontal type rollers. Further, since the friction is accurately controlled, overrunning is eliminated and the operation of the device is much more uniform.

It will thus be apparent that my device may be simply and conveniently used with one hand only, without any fear of oversupply of paper and the like, and at the same time a very attractive dispenser is provided.

While I have shown in Figures 1 and 2 an angular displacement from right angles of approximately eighteen degrees it should be understood that with the construction of the present invention greater or lesser angular displacement may be utilized including a vertical orientation without varying the construction or the principles of operation of the invention. With the novel friction obtaining method and means of the present construction,

a wide variety of angular displacements can be utilized. Thus the holder can be mounted on surfaces other than the vertical to obtain a desired attractive mounting of the mechanism.

Referring now to Figure 3 there is shown a semi-recessed or partially recessed version of the present invention. In this embodiment a recessed chamber 30 is formed with a base portion 32 and a curved wall portion 34 together with suitable flanges for mounting on a wall or other surface. The spindle 18' is then mounted in a hole 26' in the plate portion 32 of the shell 30 in a manner similar to that of Figure 2 such that a controlled friction is obtained on the rotation of the spindle and the roll of paper positioned thereon. It thus should be apparent that the present invention may be applied in several different manners each as may be best suited to the requirements of a particular use.

While there are given above certain specific examples of this invention and its application in practical use, it should be understood that they are not intended to be exhaustive or to be limiting of the invention. On the contrary, these illustrations and explanations herein are given in order to acquaint others skilled in the art with this invention and the principles thereof and a suitable manner of its application in practical use, so that others skilled in the art may be enabled to modify the invention and to adapt and apply it in numerous forms each as may be best suited to the requirement of a particular use.

I claim:

1. A roll holder for use with rolls of paper, foil or like sheet material of the type having a tubular core which comprises in combination an angle bracket having a mounting portion and a roll holding end portion, said mounting and roll holding end portions being disposed at an angle of less than ninety degrees, a hole in said roll holding end portion, a spindle rotatably mounted in said hole on the roll holding end portion of said bracket, said spindle being adapted to receive thereon the roll of paper, foil or like sheet material to be mounted on said bracket, said spindle having a bottom flange portion adapted to contact the upper surface of said bracket member, washer means mounted about said spindle on the underside of said bracket, and the end of said spindle being formed over said washer for rotatably secur-

ing said spindle within said hole in frictional contact with said bracket whereby the tearing of portions of the paper, foil or like sheet material from a roll thereof disposed in said holder when at an angle less than ninety degrees to the axis of said roll, will cause said spindle flange to engage said bracket member and control rotation of said roll so that only the desired amount is removed therefrom.

2. A roll holder for use with rolls of paper, foil or like sheet material having a tubular core therein which comprises in combination a flat angular bracket having a base portion adapted to be mounted on a generally vertical wall surface and a roll supporting end portion extending angularly outwardly from said base portion at an angle of less than ninety degrees, bracing means joining said roll supporting end portion to said base portion of said bracket, a spindle mounted on said roll supporting end portion adapted to receive thereabout a roll of paper, foil or the like, a base flange portion on said spindle having a diameter greater than said spindle and less than the diameter of the roll to be received thereon, said base flange portion receiving thereon the bottom of said roll of paper, foil or the like and holding it out of contact with said bracket, said flange portion frictionally engaging the upper surface of said angular bracket to control rotation thereof, and spindle mounting means for maintaining said flange in contact with said bracket, whereby said roll of paper, foil or the like is held out of contact with said bracket and said spindle is held in a controlled frictional engagement with said bracket for a uniform rotation thereof upon application of forces thereto at an angle less than ninety degrees to the axis thereof.
